GOLF CLUB HEAD

Howard J. Henrich, 37 Rogers Road,
East Longmeadow, Mass.

Filed Feb. 20, 1961, Ser. No. 63,997

Term of patent 14 years

(Cl. D34—5)

Fig-1

Fig-2

I claim:

The ornamental design for a golf club head, substantially as shown.
